UNITED STATES PATENT OFFICE.

WILFRED LEWIS, OF HAVERFORD, PENNSYLVANIA.

PIPE WRENCH.

Application filed November 12, 1923. Serial No. 674,183.

The present invention relates to improvements in pipe wrenches and has for one of its objects the provision of a simple, effective, cheap and superior type of wrench, 5 very light and strong and easily adjusted and held in position ready for immediate use.

The wrench consists of few parts so arranged as to give a limited amount of flexibility in the gripping jaws and the maximum strength consistent therewith and a simple adjustment for any size of pipe from the smallest commercial size to the largest within its range of service as determined 15 for the size and length of hand lever employed.

Other objects of the invention will appear from the following description, and the invention will be claimed at the end 20 hereof.

In the following description reference will be made to the accompanying drawings forming part hereof and in which—

Figure 1 is a side elevation, partly in 25 section, and with handle extension broken off to save room, showing the wrench as used in gripping a pipe, with a latch on to the handle bar by which the jaws are quickly adjusted and held securely in place.

Fig. 2 is a front elevation of Fig. 1 with the pipe omitted, and

Fig. 3 is a side elevation, partly in section, and to smaller scale, of the wrench shown in the other figures, fitted with inserted teeth and a modification of holdfast adapted for closer rather than quicker adjustments.

Referring to Figs. 1 and 2, H is the handle bar, a forging provided with teeth 1, 40 at its end to engage the pipe indicated at P. On the handle bar H, a sliding sleeve or stirrup S is mounted to carry the bar B, and the latch L, provided with teeth 2, and made to engage or disengage mating teeth 3, 45 formed in the bar H. The bar B is attached to the stirrup S, as by pins or rivets 4, thus enclosing the handle bar H, upon which it can be adjusted. The upper end of the bar B, carries the swinging jaw J on the center C, shown as a pin or rivet. The jaw J is generally book-shaped and is stamped or milled out to provide a groove on its concave face. The walls of the groove embrace a part of the handle bar H and give it a firm lateral support, and the space between the walls of the groove is utilized to

enclose the spring 5 which engages the notch 6, in the end of the bar B, and is held against the bottom of the groove in the jaw J by the cross pin 7.

Clearance is provided between the sliding bar B and the bottom of the groove in the swinging jaw J, as at A, so that the spring 5 may tilt the jaw J (counter-clockwise as shown in Fig. 3) a limited amount when no pipe is engaged and be held in readiness to take hold when pressed against a pipe and driven back as far as the clearance A permits. The spring thus located is housed to be protected against damage in service, and, 70 having a limited amount of deflection, its durability is insured. The groove in the swinging jaw J provides a double working face with teeth 8, and this double face is opposed by a single face on the handle bar, the described faces helping to properly position the wrench or the pipe and make the jaws more effective. The swinging jaw J is shown, Fig. 1, in its mean position between stops, and in this position the gripping face 75 which carries the teeth 8 is a segment of a logarithmic spiral having a constant obliquity to intersecting circular arcs from center C made to approach but not to exceed the angle of friction between the teeth and the pipe. This angle of friction depends chiefly upon the sharpness of the teeth, and when they are kept in good working order, it is believed an obliquity of 25° may safely be adopted. Of course smaller angles may 80 be used, but they tend more to crush or distort the pipe than to turn it, and a wrench with gripping teeth easily renewed or sharpened can be made in this way to 85 act at a large angle of obliquity and meet a longfelt want.

The logarithmic spiral, or curve of constant obliquity to intersecting circular arcs struck from the center C may be approximated with sufficient accuracy for the purpose by a circular arc, and this moves parallel to itself as the sleeve or stirrup S moves up or down to adjust for different sizes of pipe.

The opposing jaw with teeth 1 may also 105 be a circular arc to the same radius as that of 8 but set at an angle thereto of some 15° or thereabouts to give a wider opening at the mouth of the jaws than at their throat and permit the jaw J to be swung back as 110 far as the clearance A permits by pressing a pipe between the jaws. In this way the

gripping jaws are made to engage a pipe of any size within the capacity of the wrench at approximately the same angle between tangents to the jaws at their points of contact and since the contact points may shift with the position of the pipe engaged whether large or small the wear on the jaws becomes distributed over their entire length of face, instead of being concentrated upon a limited arc of action as is generally the case, greatly improving their durability.

Referring now to the latch L, Fig. 1, carried on the pin 9, in the stirrup S, it will be seen that this is held against the handle bar H by the spring 10, anchored in the bar B, and that the latch L has an extension 11 forming a trigger by which it may be disengaged from the handle bar H. When so disengaged the stirrup S held between thumb and forefinger, can be moved quickly up or down to engage a pipe, and upon releasing the trigger 11, the latch engages the handle bar H to anchor the jaw J against any pressure applied. It will be seen that the spring 10 is also protected and enclosed by the stirrup S and that there are no delicate parts in this wrench exposed to damage by rough usage.

In the modified form of wrench shown in Fig. 3, the swinging jaw J' is made to carry in its groove the toothed segment 12 held as by pins or rivets 13, while the handle bar H' carries upon its gripping end the bifurcated segment 14 pinned thereto as at 15. In this way the single and double gripping faces are reversed and it is possible to keep the wrench in good working order by simply sharpening or renewing from time to time the single toothed segment 12. On the double toothed segment 14, the pressure is more direct, and the danger of slipping is so remote that this part of the wrench may never require attention.

It will be understood that the pipe wrench as shown in its preferred construction, Figs. 1 and 2, must have longer gripping jaws to cover the spacing of the notches which engage the latch L, than the jaws required where a closer adjustment is attainable as in

Fig. 3. The modified construction therefore, may sometimes be preferred for its compactness while the other will be preferred for its quicker adjustment, but in either case I believe the inserted tooth segments have obvious advantages in the construction and maintenance of a pipe wrench.

In Fig. 3, 16 is an adjusting worm mounted on the sliding bar B' and meshing with rack teeth 17 on the handle bar H'.

It will be obvious to those skilled in the art that modifications may be made in details of construction and arrangement and mere matters of form without departing from the spirit of the invention which is not limited to such matters or otherwise than the prior art and the appended claims may require.

I claim:

1. A wrench having a groove provided in the concave face of its swinging jaw and extending throughout the length of the jaw, a pivot for the swinging jaw, a handle bar equipped with an opposing jaw and embraced by the portions of the side walls of the groove that lie between the pivot and said opposing jaw, a sliding bar adjustably mounted on the handle bar and also embraced by said portions of the side walls and to the end of which the swinging jaw is pivoted, and a spring housed in said portions of the side walls and interposed between the swinging jaw and sliding bar.

2. A wrench having a groove provided in the concave face of its swinging jaw and extending through the ends of the jaw, a handle bar equipped with an opposing jaw and embraced by the side walls of the groove at the end portion of the handle bar, a sliding bar embraced by said walls and to the end of which the swinging bar is pivoted, a stirrup embracing the handle bar and sliding bar, a spring arranged in said groove and interposed between the end of the sliding bar and the swinging jaw, and adjusting means interposed between the handle bar and the sliding bar.

WILFRED LEWIS.
